UNITED STATES PATENT OFFICE.

CHARLES L. DAHLBERG, OF DES MOINES, IOWA.

BOOK-HOLDER AND LINE-GUIDE.

1,317,004.

Specification of Letters Patent. Patented Sept. 23, 1919.

Original application filed August 20, 1917, Serial No. 187,242. Divided and this application filed July 31, 1918. Serial No. 247,685.

To all whom it may concern:

Be it known that I, CHARLES L. DAHLBERG, a citizen of the United States, and resident of Des Moines, in the county of Polk 5 and State of Iowa, have invented a certain new and useful Book-Holder and Line-Guide, of which the following is a specification.

The object of my invention is to provide 10 a book holder and line guide of simple, durable and inexpensive construction, so arranged that it may be readily, quickly and easily adjusted for holding books of all ordinary sizes in such position that the operator 15 can readily read from the book, and when copying from the book the lines of printed material may be indicated for the convenience of the operator.

More particularly it is my object to provide 20 a combined adjustable line indicator and weight for holding the book open and the leaves flat, which indicator and holder may be readily and easily adjusted to lie substantially flat on books of any size.

25 My invention consists in the combination with a book holder having automatically adjustable or self-equalizing side supports for the opposite sides of the book, with a combined weight and line indicator adjustably 30 mounted so that the line indicator may lie substantially flat on books of any size, and also with a means for adjusting the book holder relative to the line guide for accommodating the device to books of unusually 35 great thickness, whereby the objects contemplated are attained as hereinafter more fully set forth, pointed out in my claim, and illustrated in the accompanying drawing, in which:

40 Figure 1 shows a perspective view of my improved device, part of one of the book supporting members being broken away to show the adjustable feature.

Fig. 2 shows an enlarged, sectional view 45 illustrating the adjusting bolt for the book holder.

Fig. 3 shows an enlarged, detail, plan view of the adjustable bolt for the book holder, and the equalizing bar and connected 50 parts.

Fig. 4 shows a detail front view of the adjustable swinging support for the supporting rod of the line guide.

Fig. 5 shows a side view of same, the dotted lines showing the support for the line

guide rod in different positions of its adjustment; and

Fig. 6 shows a similar detail view illustrating the means for limiting the upward movement of the line guide rod support. 60

Referring to the accompanying drawings, I have used the reference numeral 10 to indicate the base of the device, upon which are the side guide plates 11. At the longitudinal center of the base is a guide strip 12, 65 and between the guides 11 and 12 on each side is a sliding book supporting base plate 13.

Hinged to each book supporting base plate 13 is a book support 15, and these book supports are capable in one position of lying flat against the base member 13, or of being supported in an upwardly and rearwardly inclined position, as shown in Fig. 1, by means of the pivoted lugs 15^a. At the bottom 70 of each book support is a shelf 16 to engage and hold the lower edge of the book.

At about the central portion of the guide 12 and base 10 is a slot 17 extending parallel with the sides of the base. At the bottom 80 of the slot is a recess 18 to receive the head 19 of a bolt 20. At the upper end of the bolt is a nut 21 mounted on the bolt, and a washer 22 is also placed on the bolt, which washer has an upwardly extending flange 23 85 to engage the nut.

Pivotedly mounted on the upwardly extending part 23 of the washer 22 is an equalizing bar 24 extended transversely of the base. This equalizing bar is provided with slots 90 25 at its ends, through which slots the pins 26 are projected, and which pins are supported in the book holder base members 13.

By this arrangement it is obvious that when one of the base members 13 is moved 95 forwardly, the other is moved rearwardly to a corresponding degree, and it is also obvious that by loosening the nut 21 the equalizing bar 24 and both of the sliding base members 13 may be adjusted forwardly or rearwardly, as desired.

Secured to the front of the central guide 12 is a base 28 having an upright 29. This upright is provided with a shoulder at 30, for purposes hereinafter made clear. 105

Mounted on the opposite sides of the upright 29 are the two bars 27 constituting the support for the line guide rod. These bars 27 are pivotally connected to the support 29 by the pivot pin 31, and a limiting 110

pin 32 is fixed to these bars and is designed in one position to engage the shoulder 30 so that the forward movement of the supporting bars 27 is thereby limited, although 5 the movement in a rearward direction is not limited. At the upper part of the supporting bars 27 the line guide supporting rod 33 is inserted between the bars 27, and is capable of being firmly and adjustably 10 clamped therein by the set screw 35.

Slidably mounted upon the rod 33 is a combined weight and line guide 34, adjustably mounted on the rod 33 by the set screw 35^a. Formed in the bars 27 is a series of 15 openings 36, into which the set screw 35 may be inserted, if desired, for giving additional adjustment to the line guide rod 33.

The shape of the combined weight and 20 line guide is such that its flat base will lie substantially flat upon the pages of a book held in the book holder, and its upper edge is tapered to form a thin, straight edge to 25 serve as a line guide.

In practical use and assuming that the 25 device is adjusted to the position shown in Fig. 1, then an operator places a book in position resting upon the book holder members 15. If the book is opened at its approximate central portion, then the two 30 book holders 15 will be substantially in line with each other. If, however, the book is opened near the front or back, then one of the book holder members 15 is pushed rearwardly and the other moved forwardly a 35 corresponding distance, so that the two open leaves of the book will be substantially in line with each other across the holder.

In a device of this kind, it is desirable 40 that the combined weight and line guide shall lie approximately flat on the printed pages, and this means that the line guide rod 33 must be substantially parallel with the open face of the book. To accomplish this adjustment, the operator need only 45 loosen the set screw 35 and then swing the rod 33 to position substantially parallel with the open face of the book, and then

tighten the set screw, whereupon the line guide rod will be in position and will remain substantially parallel with the face of 50 the book, and this adjustment is not disturbed when the entire line guide is swung away from the book and back again, either to replace the same book or another one of 55 the same thickness.

As fast as the printed matter on the exposed pages of the book has been read, the line guide 34 is adjusted by the set screw 35^a, and this adjustment may proceed until the reading of the exposed pages has been 60 finished.

In the event that an unusually thick or thin book is being used, and it is not convenient or possible to provide the necessary 65 adjustment by means of the line guide rod adjusting device, then the operator may readily and quickly adjust the bolt 20 to move the entire book holder device either forwardly or rearwardly with relation to the line guide rod supporting device, although 70 this adjustment is necessary only in connection with unusual sizes of books.

I claim as my invention:

In a device of the class described, designed to be mounted on a holder comprising 75 a base and an inclined holding device, having means for varying the inclination and longitudinal position of the latter relative to the base, an upright adapted to be secured to a base, a bar having its lower end 80 pivoted to the upright and having a plurality of spaced openings adjacent to its other end, means for limiting the pivotal movement of said bar in one direction, a rod having one end adapted to be selectively 85 pivoted in one of said openings, means for fixing said rod from pivotal movement relative to the bar, a combined weight and line guide slidably mounted on said rod, and means for fixing the guide against movement relative to the rod.

Des Moines, Iowa, July 15, 1918.

CHARLES L. DAHLBERG.
